UNITED STATES PATENT OFFICE

WILLIAM STEININGER, OF BERWYN, ILLINOIS, ASSIGNOR TO W. D. ALLEN MANUFACTURING COMPANY, OF CHICAGO, ILLINOIS, A CORPORATION OF ILLINOIS

SPRINKLER

Application filed May 28, 1928. Serial No. 281,208.

This invention relates to the art of hose sprinklers, and has reference more particularly to an improvement in sprinkler heads or nozzles of the type adapted to deliver the water in the form of either a full stream or a spray. A sprinkler of the type to which my present invention relates is disclosed in Letters Patent to Henry Gibbs, No. 1,086,288, dated February 3, 1914, and my present invention is in the nature of an improvement on the sprinkler of the aforesaid patent.

In the device of the said patent there is provided a discharge nozzle having a reduced peripherally grooved cylindrical part formed with an eccentric discharge opening, a deflecting plate or fin having its inner end extending along one side of the nozzle, and its outer end bent toward the axis of the nozzle, and a yoke or collar embracing and adjustable around said grooved portion of the nozzle and having flanged ends engaging the edges of the deflecting plate and supporting the same. Said yoke or collar forms the means for mounting the deflecting plate on the nozzle with capacity of adjustment around the latter, whereby a full stream or a spray may be delivered; and the object of my present invention is to improve the mounting means of the deflector plate so as to shorten and simplify the structure, reduce the number of parts, and reduce the cost.

Two slightly differing practical embodiments of the present invention are illustrated in the accompanying drawing, in which—

Fig. 1 is an elevation;

Fig. 2 is an axial section on line 2—2 of Fig. 1;

Fig. 3 is an axial section of a modification.

Referring to Figs. 1 and 2, 10 designates a nozzle interiorly threaded for connection to the threaded end of a hose or pipe 11, with an interposed packing washer 12, preferably of rubber. On the outer end or face of the nozzle 10 is formed a low circular bearing boss 13 that is coaxial with the nozzle 10. The nozzle 10 is further formed with an eccentric discharge opening 14 extending through a nipple 15, which latter is encircled by the boss 13. 16 designates the deflector or fin, consisting of an approximately flat piece of

metal formed near its inner end with an integral laterally offset shank portion 17 and a centrally apertured base plate 18 that has a bearing fit on the boss 13 and lies in contact with the face of the nozzle 10. After the base plate of the deflector has been mounted on the boss 13, the marginal portion of the latter is swaged over the inner periphery of the base plate 18 forming a lip or flange 19 that securely confines the base plate on the outer end of the nozzle. The lip 19 clamps the base plate 18 of the deflector with sufficient friction to permit the deflector and its base plate to be bodily shifted around the boss and to hold the deflector in adjusted position. It will be observed that the deflector 16 is inwardly inclined toward the axis of the nozzle, so that, with the parts positioned as shown in Fig. 2, the jet of water issuing from the nipple 15 strikes the inner face of the deflector 16 and is sprayed thereby. When, however, the deflector 16 is shifted 180° from the position shown in Fig. 2, the jet will pass the deflector in the form of a solid stream. By shifting the deflector to intermediate positions, the jet is partially sprayed.

In the embodiment shown in Fig. 3, the nozzle is formed in two parts, an outer shell portion 10' and a central body portion formed as a plug 10^a that is driven tightly into the shell portion 10'. The plug 10^a is formed with the nipple 15' and eccentric discharge opening 14' extending therethrough, with the low bearing boss 13', and with a preformed annular lip or flange 19'. In assembling these parts, the apertured base 18 of the deflector is laid on the outer face of the shell portion 10' of the nozzle, and the body portion or plug 10^a is then driven through the base portion 18 and into the shell portion 10', the lip or flange 19' having a friction bearing on the base 18. This construction, as compared with that shown in Fig. 2, has the disadvantage of a greater number of parts, but it has the advantage of a preformed retaining lip or flange which does not require to be swaged down into place.

By comparison of the above structures with that disclosed in the Gibbs patent hereinabove referred to, it will be seen that the new con-

struction herein disclosed considerably shortens the total length of the nozzle and deflector plate, reduces the number of parts by forming the deflector plate and its shank and base all in one piece, and thus considerably reduces the cost of manufacture.

I claim—

- 10 1. A sprinkler of the type described, comprising a discharge nozzle formed with an eccentric discharge nipple and provided on its outer end with a low boss coaxial with said nozzle and surrounding said nipple, a deflector having a laterally extended flat apertured base plate seated on the outer end of said nozzle and frictionally fitted on and adjustable around said boss whereby to shift said deflector into and out of alignment with the nipple discharge orifice, and means for confining said base plate on said boss.
- 15 2. A sprinkler of the type described, comprising a discharge nozzle formed with an eccentric discharge nipple and provided on its outer end with a low circular bearing boss coaxial with said nozzle and surrounding said nipple, a deflector blade having a laterally extended flat apertured base plate seated on the outer end of said nozzle and frictionally mounted on and adjustable around said boss, and an annular lip on the outer end of said
- 20 30 boss overlapping and confining said base plate on said boss and permitting said base plate to be adjusted around said boss whereby to shift said deflector into and out of alignment with the nipple discharge orifice.
